UNITED STATES PATENT OFFICE.

ALGERNON S. PHELPS, JR., OF CHICAGO, ILLINOIS.

CARBID-FEED FOR ACETYLENE-GENERATORS.

No. 878,310.

Specification of Letters Patent.

Patented Feb. 4, 1908.

Application filed May 29, 1906. Serial No. 319,397.

To all whom it may concern:

Be it known that I, ALGERNON S. PHELPS, Jr., citizen of the United States of America, residing at Chicago, Cook county, Illinois, 5 have invented certain new and useful Improvements in Carbid-Feed for Acetylene-Generators; and I do hereby declare the following to be a full, clear, and exact description of the invention, such as will enable 10 others skilled in the art to which it appertains to make and use the same.

My invention relates to improvements in acetylene gas generators and in particular to an improved carbid feed.

15 The object of my invention is to provide a carbid feed which will comply with all the well known requirements of the Underwriters' Association, and which will be capable of automatically adjusting itself so 20 as to feed various sizes of calcium carbid with equal facility and with uniformity, thus insuring a close regulation of the gas pressure.

Having these objects in view, the invention consists in an improvement upon the 25 carbid feed mechanism set forth in Patent 783732 heretofore granted to me. By the present improvement I have provided means operating both to prevent the caking of the carbid within the mouth of the magazine 30 and to prevent the discharge of carbid therefrom during the feeding motion of the shoe.

The invention as hereinafter more fully described and as particularly set forth in the claims, will be readily understood by an 35 inspection of the accompanying drawing, in which a preferred form of the device is illustrated.

In these drawings Figure 1 is a vertical 40 section through the lower portion of the magazine at one position of the feed; Fig. 2 is a similar view at the other position of the feed; Fig. 3 is an elevation, partly broken away, showing the feed device in connection with the operating mechanism; and Figs. 4, 45 5 and 6 are details.

Referring to the drawings more in detail, the magazine casing *a* of any ordinary construction, has supported therein upon adjustable stops *b*, a carbid holder *c* provided 50 with a downwardly inclined deflecting plate or shed *d*, serving to confine the egress of the carbid to one side of the magazine. Below this shed *d* the wall *e* of the lower funnel shaped portion of the magazine is disposed 55 at substantially right angles to the deflecting plate *d*, from which it will be seen that the

carbid approaches the discharge opening through this chute from one side. A feed shoe *f* is supported by a yoke pivoted at *g* to swing below and closely adjacent to the 60 mouth of the chute, said mouth and the shoe both being concentric to the pivotal point *g*, whereby the reciprocating motion of the feed shoe across the mouth is unimpeded by reason of the fact that the space 65 between the two is at all times constant.

An open hook link *h* is pivotally connected with the feed shoe *f* and with its open hook end engages the deflected portion of a rock shaft *i*, which is arranged to be rocked upon 70 the descent of the gasometer bell in any approved manner, for instance, as shown in my patent above referred to.

The device thus far described is substantially identical in construction and operation 75 with that set forth in detail in my patent above referred to and needs no further description.

Fixed to the lower rear portion of the shoe *f* by casting integrally therewith or 80 riveted or bolted thereto is a cam hook *l* which moves with said shoe. Upon ears carried by the lower portion of the magazine is pivoted at *m* a dog *n* formed as a bell-crank lever, counterweighted at *o* and provided with a cross bar *p* lying below and transversely of a series of bars *q*, pivoted at *r* to the magazine. The bars *q* are provided 85 with fingers *s* curved concentrically to the pivotal point *r* and arranged for reciprocation independently of each other within the slot *t* arranged in the rear of the magazine throat adjacent to its mouth.

The relation of the several parts just described is such that when the feed shoe 95 occupies a position beneath the mouth of the magazine the pin *u*, of the dog, is, by the cam surface of the hook *l*, depressed and the bars *q* are held in an elevated position by the cross bar *p* with the fingers *s* retracted from the 100 slot *t*, leaving the throat of the magazine unobstructed, so that the carbid may flow freely therethrough into the shoe *f*. As the gasometer bell descends and the shaft *i* is rocked, the shoe is thrown to the rear from the mouth 105 of the magazine, dropping into the generator its charge of carbid. This movement of the feed shoe causes the cam hook *l* to move away from the pin *u* of the dog *n*, permitting the bars *q* to drop the fingers *s*, which 110 pass through the slot *t*, and across the throat of the magazine until they contact with the

front wall of the same, effectually shutting off any downward flow of the carbid during the time that the shoe is removed from the mouth of the magazine.

5 By arranging the several bars *q* with their fingers *s* entirely independent of each other, a certainty of operation is attained by reason of the fact that should one of the fingers meet with an obstruction, such as a large 10 lump of carbid, the other fingers will pass to their proper position independently of the obstructed one. This would not be the case if the several teeth *s* were carried by one bar after the manner of the teeth of a comb.

15 Within the chute leading from the magazine to the feed shoe is arranged a deflector *v* formed by a protuberance on the upper wall of the part *e* immediately in front of the opening *t*, its function being to guard the 20 opening from the direct line of flow of the carbid so as to facilitate the entrance of the fingers and prevent their jamming by particles of carbid wedging between them and the sides of the opening.

25 The relation of the pins *u* and the cross bar *p* to the pivotal point *m* and the curve of the cam hook *l* is such that the bars *q*, with their fingers *s*, remain stationary during the initial movement of the feed shoe in either direction.

30 Just before the feed shoe clears the mouth of the magazine, the fingers *s* are dropped quickly into a position to shut off the magazine chute, their rate of travel being much greater than that of the shoe; likewise the 35 fingers remain in this position until the shoe has again practically closed the mouth of the throat when they are as quickly withdrawn.

40 The particular features of construction utilized for the operation of these parts might be modified to a considerable degree without departing from the spirit of my invention, which resides primarily in the arrangement of independent fingers acting as a 45 cut-off to prevent the flow of the carbid at certain times and also to break up or prevent the caking of the carbid within the magazine throat.

Having thus described my invention, what I claim as new and desire to secure by Letters 50 Patent, is:

1. In a carbid feed, the combination, with a feed shoe, of a plurality of fingers tending to simultaneously interpose from above into the path of travel of the carbid to the shoe, 55 and means for controlling said fingers.

2. In a carbid feed, the combination, with a feed shoe, of a plurality of independent fingers tending to interpose from above into the path of travel of the carbid to the shoe, 60 and means actuated by the movement of the shoe to control the fingers.

3. In a carbid feed, the combination, with a feed shoe, of a plurality of fingers tending to interpose from above into the path of travel 65 of the carbid to the shoe during the

feed movement of the shoe, and means actuated near the close of the return movement of the shoe to withdraw said fingers.

4. In a carbid feed, the combination with a feed shoe, of a plurality of independent 70 fingers pivotally mounted in such a position as to be capable of interposition from above into the path of travel of the carbid to the shoe, a pivoted dog controlling the movement of the fingers, and means carried by 75 the shoe and actuated during its feed movement to permit the interposition of the fingers in the path of the carbid and near the close of the return movement of the shoe to withdraw said fingers. 80

5. In a carbid feed, the combination with a feed shoe, of a plurality of independent fingers pivotally mounted in such a position as to tend by gravity to interpose from above into the path of travel of the carbid to the 85 shoe, a pivoted dog restraining the movement of the fingers, and means carried by the shoe and actuated after the beginning of its feed movement to permit the interposition of the fingers in the path of the carbid and 90 near the close of the return movement of the shoe to retract the dog to a position to withdraw said fingers, the movement of the fingers being accelerated beyond that of the shoe. 95

6. The combination, with a carbid magazine, and a feed shoe, of a plurality of independent fingers pivotally mounted in such a position as to interpose from above into the path of travel of the carbid from the magazine to the shoe, a pivoted dog controlling the movement of the fingers, a cam hook carried by the shoe and acting upon the dog during the feed movement of the shoe to cause the interposition of the fingers and 105 during the return movement of the shoe to withdraw the fingers, the relation of the cam surface of the hook to the dog being such as to accelerate the movement of the fingers beyond that of the shoe. 100

7. The combination, with a magazine, a feed shoe, and a chute leading from the magazine to the feed shoe, of a cut-off device comprising spaced fingers entering the chute through an opening out of the direct line of 115 travel of the material therein.

8. The combination, with a magazine, a feed shoe, and a chute leading from the magazine to the shoe, one of the walls of the chute provided with a deflector and an opening behind said deflector, of a cut-off device comprising spaced fingers arranged to enter the chute through the opening, and means to control the operation of the cut-off device and feed shoe. 120

9. The combination, with a magazine, a feed shoe, and a chute leading from the magazine to the shoe, a plurality of fingers arranged to interpose into the path of travel of the material through the chute to the 130

shoe, and means mounted in said chute to deflect the flowing material from the point of entrance of the fingers.

10. The combination, with a carbid magazine, a feed shoe, and a chute leading from the magazine to the shoe, a plurality of fingers tending to interpose into the path of travel of the carbid through the chute to the shoe, and a protuberance formed upon the wall of said chute immediately in front of the

point of entrance of the fingers to deflect the carbid therefrom.

In testimony whereof I affix my signature to this specification, in the presence of two witnesses.
